METHOD OF STERILIZING LIQUIDS AND FILLING CONTAINERS

Henry F. Glunz, Astoria, Long Island, N. Y.

Original application August 6, 1936, Serial No. 94,528. Divided and this application May 6, 1937, Serial No. 141,047

3 Claims. (Cl. 99—218)

The principal objects of the invention are to provide liquids in containers in a sterile condition, so that they may be transmitted to the consumer in a thoroughly sanitary manner entirely free from harmful bacteria or disease germs.

The principal feature of the invention resides in the novel method of treating the liquid and filling same into containers in a series of continuous steps whereby the liquid is drawn or allowed to flow into a vacuumized receiving chamber in attenuated form through a sterilizing zone and air is concurrently evacuated from containers to permit the sterilized liquid to pass directly from the vacuumized interior of the chamber to the vacuumized interior of the containers free from contamination with germ-laden air.

The accompanying drawing is a vertical mid-sectional elevational view of an apparatus particularly suitable for the carrying out of my method.

While various forms of apparatus may be employed for putting my method into effect I have chosen to define the method in connection with a particular apparatus for purposes of illustration, which apparatus forms the basis of my pending application Serial No. 94,528, filed August 6, 1936, from which this application has been divided, and in order that the method should be fully understood the construction of such apparatus is referred to but not claimed herein.

The device as herein shown consists of a base 1 of cylindrical form supporting a central shaft 2 encircled by a sleeve 3 having an externally threaded upper end 4.

A cylindrical casing 5 formed with a hollow central boss 6 is threaded on to the threaded upper end of the sleeve 3 for vertical adjustment, the top of the boss being sealed.

The casing 5 is closed at the top by a cover 7 which has a suitable air-tight joint therewith and the centre of the cover is provided with a cylindrical extension 8 over which a cap 9 is fitted and which is air-sealed by a suitable friction washer 9'.

An exhaust tube 10 is secured in the cap 9 and is here shown connected to a vacuum machine indicated at A to exhaust the air from the casing 5.

A liquid supply tube 11 is mounted in the cap 9 and extends under the cover 7, preferably close to the inner cylindrical wall of the casing 5, and is formed with a broad spreader nozzle 12 adapted

to discharge a broad thin sheet of liquid in a downward direction.

Secured to suitable supports on the inner wall of the casing 5 is a shelf 13 arranged immediately below the spreader nozzle 12 and this shelf slopes downwardly and inwardly and provides a wide sloping surface and the broad thin sheet of liquid impinges thereagainst angularly so that it is spread in an effective manner in the form of a thin film.

Arranged at a suitable distance above the shelf 13 and extending across same at the zone where the liquid is spread out into film form, are one or more devices 14, preferably mercury vapour lamps of a suitable design which produce rays having the capability of sterilizing fluids passed underneath over the shelf 13 in a thin film. The action of the sterilizing rays is enhanced by the fact that the flowing liquid is attenuated by the presence of the vacuum in the chamber and the liquid is thoroughly sterilized.

If milk is being treated in this apparatus, the passage of a thin film thereof under the ultraviolet rays of the sterilizing lamps will have the definite effect of irradiating the same and very materially increasing its vitamin D content. The sterilized and irradiated liquid flowing over the shelf 13 is discharged into the casing 5 and the height of the level of liquid therein may be regulated by a suitable float controlled valve 15 arranged in the liquid supply tube 11.

The bottom 16 of the casing preferably slopes downwardly from the centre boss 6 and a plurality of bosses 17 extend downwardly therefrom adjacent to the periphery. Each of the bosses 17 is bored centrally to house a vertical plunger 18, which is held downward by a coil spring 19, the lower end of each plunger 18 having a flange 20 with a rubber gasket to engage in sealed contact with the rim of a bottle or other container 21.

Each of the bosses 17 is provided with a vertical duct 22 opening to a tube 23 extending upwardly into the casing 5 and having a port at the lower end opening into the bored recess housing the plunger 18, and the plunger is provided with a duct 24 adapted to open to said port at a predetermined point in the upward movement of the plunger to permit the vacuum in the casing to exhaust the air from the container engaging the plunger flange.

Each plunger has a second vertical duct 25, which communicates with a port at the lower end of a duct 26 in the boss opening to the interior of the casing upon the plunger being moved upwardly to a point where the vacuum duct is 55

closed to permit the flow of the liquid from the chamber 5 into the container under the influence of the vacuum, which will have been created in the container.

5 It will be understood that by effecting an upward movement of the container against the plunger 18, the air in the container is first exhausted through the registering ducts and tube 23 to a point above the level of the liquid in the 10 casing 5, and immediately thereafter the container is filled with liquid by the suction of the vacuum therein, or by reason of the fact that the vacuum prevailing in the container is substantially equal to the vacuum within the casing so 15 that the liquid will quickly fill the container and such liquid will not be contaminated by contact with air which might be germ-laden, the exhausted air being cleared from the top of the tubes 18 without contaminating the liquid in the 20 casing 5.

The bottles or other containers to be filled are placed on tables or platens 27 supported on vertical plungers 28 mounted in the base structure and these are operated to lift a predetermined 25 distance by means of a suitable cam 29 engaging a roller contact 30 on the bottom of the plunger 28, a suitable guide 31 being mounted on the centre standard or sleeve 3 to position or hold the containers in a suitable relation to the platens, allowing free vertical movement thereof.

The casing 5 is shown mounted on a threaded support, so that it may be adjusted vertically to suit various lengths of containers to be filled, but other forms of vertical adjustment may be made 35 and the means for lifting the containers may be varied considerably in order to impart the desired vertical motion or motions to the containers.

In carrying out my process in connection with the above-described apparatus, the casing 5 is sterilized, then the air is evacuated therefrom, 40 the liquid to be treated being allowed to flow therewith under the action of gravity and the vacuum in the casing, through the spreader nozzle and spread out in a broad surface film, which film is rendered extremely thin by the presence 45 of the vacuum and is readily penetrated in its flow by the irradiating sterilizing rays and all germ and bacilli are eliminated within the actual dispensing casing.

50 The sterile liquid then falls into the body of

the casing where the liquid level is maintained below the irradiating surface by the operation of the float valve.

The containers to be filled are sterilized in a suitable manner and fed by suitable mechanism 5 or by hand to the vertically operable tables or platens, and these are operated to raise the containers to engage the valving plungers located in the bottom of the main casing to first effect the evacuation of the air from the containers 10 and then direct the liquid into the vacuumized containers and the containers are then sealed in any suitable manner.

What I claim as my invention is:

1. In a method for the sterile filling of containers with liquid, the steps of spreading the liquid out in a thin film on a shelf in substantially uniform relation to a source of sterilizing rays while simultaneously subjecting the same to the attenuating action of a vacuum, and then 20 filling the same directly into sterilized and vacuumized containers free from contact with germ-laden air.

2. A method of sterilizing liquids and filling bottles and the like for delivery, consisting in 25 producing a vacuum in a liquid-receiving chamber, temporarily supporting a liquid in said chamber in a thin film above the liquid level therein, subjecting the film of liquid while in its supported vacuumized form to sterilizing rays, first 30 fully evacuating the air from the bottles to be filled and then causing the sterilized liquid to flow directly from the vacuumized interior of said chamber into the evacuated containers to fill the same in one operation. 35

3. A method of sterilizing liquids and filling bottles and the like for delivery, consisting in producing a vacuum in a liquid-receiving chamber, directing a flow of liquid to said chamber, spreading and supporting the liquid in a thin 40 film within the vacuumized chamber, directing sterilizing rays over said supported film, producing a vacuum within the bottles to be filled equal to the vacuum in the said chamber, and causing the sterilized liquid to flow by gravity directly 45 from the interior of the vacuumized chamber into the evacuated bottles to completely fill the same in one operation free of contaminating contact with germ-laden air.

HENRY F. GLUNZ.
